PERPETUAL CALENDAR FOR WRITING
INSTRUMENTS

Joseph Moll, Philadelphia, Pa.

Application April 8, 1933. Serial No. 665,054

5 Claims. (Cl. 40—108)

My invention relates to new and useful improvements in a perpetual calendar for writing instruments, and has for one of its objects to provide a perpetual calendar for use in connection with a writing instrumentality, such as an ordinary pen, pencil, fountain pen or the like.

Another object of the invention is to provide a simple, durable, efficient and handy device of this character wherein the writing instrumentality forms a part of the calendar mechanism which latter is adjustable so as to constitute a perpetual calendar, particularly adapted for indicating days and dates of certain years, for use as a memorandum to remind a person of some special day or date because of some particular event, such as historical and memorial dates, birthdays or when certain bills, insurance premiums and the like are due.

A further object of the invention is to provide a calendar of unique construction embodying two calendar strips each connected with a pair of shafts carrying gears which are selectively rotatable by a pinion engageable with either of the pairs of shaft gears.

A further object of the invention is to construct the basic calendar mechanism in the form of a capsule for insertion in a hollow supporting member, such as the hollow stem of a pen, pencil or the like, or a cap to be mounted upon an article, such as a pen or pencil.

A still further object of the invention is to provide a pointer carried by the supporting member for particularly indicating any particular date under a particular day.

Still another object of the invention is to provide a supplementary chart for use in connection with the calendar whereby a person is able to find any day and date of the twentieth century which will be indicated on the calendar.

With these and other ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawing forming a part of this application, in which:

Fig. 1 is a view of a writing instrumentality exemplified as a fountain pen illustrating a calendar embodying my invention applied thereto.

Fig. 2 is an enlarged vertical sectional view of the fountain pen cap showing part of the cal-

endar mechanism therein, the calendar strips being removed for sake of clearness.

Fig. 3 is an outer or upper end view of Fig. 2.

Fig. 4 is a section on the line 4—4 of Fig. 2.

Fig. 5 is a section on the line 5—5 of Fig. 2. 60

Fig. 6 is a view of the chart used as a supplement to the calendar.

In carrying out my invention as herein embodied, 10 represents a part of a writing instrument which for purposes of illustration is shown 65 herein as a fountain pen, and 11 is another part of a writing instrument, for instance a cap to cover either end of the part 10. While I have particularly illustrated the calendar in connection with a fountain pen, I do not limit myself 70 to such use as it may be embodied in other articles or manufactured as separate units in capsule form to be assembled in or on any suitable supporting device.

The part 11 or cap has a long opening 12 or 75 window running longitudinally thereof, and a small opening 13 or second window in endwise spaced relation to the long one. The openings may have sheets of transparent material 14 disposed across the same. Where said part is a 80 fountain pen cap, an end thereof may be internally threaded as at 15 for connection to the part 10.

Adjacent the opening 12 is slidably mounted a pointer 16 for movement lengthwise of said 85 opening, the purpose of which will be presently explained. By way of illustration, I have shown this pointer as provided with a body 17 fitted in a dove-tailed slot 18 contiguous to the opening 12 and substantially of the same length. 90

Inside of the part 11 is fitted a casing or capsule 19 including body walls 20, a bottom wall 21, a top wall 22, and at least two partitions 23 and 24. In the bottom wall 21 and the partition 24 are journaled a pair of spaced parallel shafts 95 25 and 26, and on the upper ends of said shafts 25 and 26, and on the upper ends of said shafts above the partition 24 are fixed gears 27 and 28 which are spaced apart.

In the top wall 22 and the partition 23 are journaled another pair of shafts 29 and 30 in 100 endwise alignment with the shafts 25 and 26 respectively, and said shafts have gears 31 and 32 fixed to their lower ends below the partition 23. In other words, both sets of gears are located in the space between the partitions 23 and 24. 105

A guide post 33 is located between the gears of both pairs, and mounted to rotate and slide on said post is a hollow sleeve shaft 34 having a knob 35 on its upper end outside of the top wall 22, and a clutch pinion 36 on its lower end 110

for selective engagement with either pair of gears.

To the shafts 25 and 26 are fixed the ends of a flexible date calendar strip 37 having day designations and dates therefor delineated thereon in a columnar form so as to be wound back and forth from one shaft to the other. Likewise, a monthly calendar strip 38 having the months and their number of days delineated thereon has its ends fixed to the shafts 29 and 30 as to be wound from one shaft to the other.

These calendar strips are threaded through spaced slots 39 and 40 in the casing at the sides of the openings 12 and 13, whereby limited areas 15 of said strips will be visible.

On the upper end of the member 11 is removably mounted a top 41 in which is a dial 42 carrying a magnetic needle 43 constituting a compass which is visible through a transparent 20 panel or lens 44 carried by the top.

A cork disc or block 45 is assembled in the part 11 below the capsule or casing to prevent any leakage of ink from reaching the calendar 25 elements.

If found desirable, the casing 19 may be made of two semi-cylindrical parts and the end walls and partitions with the other mechanism assembled in one of said semi-cylindrical parts and then the other semi-cylindrical part placed in 30 position and fastened in any suitable manner so that the resultant casing structure will be cylindrical as herein shown and described.

A chart or index card 46 may be provided as a supplement of the calendar to permit a person 35 who desires to find any date and day in any month of any year during the twentieth century, to determine which column of dates must be turned into view through the opening 12 in the part 11 of the writing instrument. The directions for using the chart or index card are included as an element of said chart which is illustrated in Fig. 6.

Various changes in form, proportion and minor details may be resorted to without sacrificing the many advantages of this invention, and of course I do not wish to be limited to the exact details of construction as these may be varied without departing from the spirit of my invention.

Having thus fully described my invention, what I claim as new and useful is:—

1. In a perpetual calendar for writing instruments, a casing for insertion in a part of said writing instrument, said casing having parallel longitudinal slots adjacent each other, two pairs of shafts journalled within said casing, two separable calendar strips having data delineated thereon, said strips being threaded through the slots whereby portions thereof are visible through openings in that part of the writing instrument in which the casing is mounted, gears on the contiguous ends of all of the shafts, and a clutch pinion for selective engagement with the gears on either pair of shafts whereby either one of the calendar strips may be wound upon either of its respective shafts.

2. The structure set forth in claim 1, in combination with a pointer movable longitudinally along one of the openings for indicating a specific designation on the adjacent calendar strips.

3. In a device of the kind described, a supporting member having a long opening formed therein longitudinally thereof and also provided with a smaller opening in endwise alignment but spaced from said longer opening, a pointer slidably

mounted adjacent said longer opening for movement lengthwise thereof, a casing fitted in said supporting member and having longitudinal slots thereon, one of which will be positioned on each side of the openings when the casing is in place, a pair of shafts journalled in the lower portion of the casing, gears on the upper ends of said shafts and in spaced relation to each other, another pair of shafts journalled in the upper portion of the casing in endwise alignment with the first mentioned shafts, gears on the lower ends of the second named shafts in spaced relation to each other and in spaced relation to the first mentioned gears, calendar strips each having its ends fixed to one pair of shafts so as to be wound on either one thereof and threaded through the slots in the casing for visibility through its respective opening in the supporting member, a post mounted in the casing, a hollow shaft rotatably and slidably mounted on said post with its upper end projecting above the end of the casing, a knob on said upper end for actuating the sleeve, and a clutch pinion carried by said hollow shaft to be selectively engaged with the pair of gears on the shafts in the lower portion of the casing or with the pair of gears in the upper portion of said casing for rotating either pair of shafts to change the visible parts of the calendar strips at the openings.

4. The structure set forth in claim 3, in combination with transparent means disposed across the openings in the supporting member.

5. In combination, a writing instrument including a cylindrical cap having a long opening formed therethrough running longitudinally thereof and also provided with a smaller opening in spaced endwise alignment with the longer opening, sheets of transparent material disposed across said openings, a pointer carried by the cap adjacent said longer opening and slidably mounted longitudinally of said opening for manual adjustment, a casing mounted in the upper end of said cap, a block cork mounted in said cap at the lower end of the casing to prevent any leaking ink from reaching the casing, said casing having longitudinal slots formed therein which are disposed adjacent the sides of the opening in the cap, a pair of parallel spaced shafts mounted in the lower portion of the casing, a calendar strip having days and dates delineated thereon in column form, said strips having its ends attached to the shafts and threaded through the slots so as to be visible through the longer opening, gears mounted on the upper ends of said shafts, another pair of spaced parallel shafts journalled in the upper end of the casing, a calendar strip having months of the year and the number of days of said months delineated thereon, said last named strip having its ends attached to the second named pair of shafts and threaded through the slots in the casing so as to be visible through the smaller opening in the cap, a post mounted in the upper end of the casing between the gears of each pair, a hollow shaft slidably and rotatably mounted on the post and projecting above the upper end of the casing, a clutch pinion mounted on the inner end of said hollow shaft for selective engagement with either pair of gears for actuating either pair of shafts, a knob on the outer end of said hollow shaft whereby the clutch pinion may be controlled manually, and a top removably mounted on the upper end of the cap for normally enclosing the knob.
